(57) **CLAIM**

The ornamental design for a hat organizer, as shown and described.

DESCRIPTION

FIG. 1 is a front perspective view of a hat organizer, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged partial view taken from broken short dash-long dash rectangle 9 in FIG. 1;

FIG. 10 is an enlarged partial view taken from broken short dash-long dash rectangle 10 in FIG. 2;

FIG. 11 is a front perspective view of the hat organizer shown in a folded configuration;

FIG. 12 is a rear perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof; and,

FIG. 18 is a bottom view thereof.

The short dash-long dash lines represent the enlarged partial view regions and form no part of the claimed design.
